(No Model.)

A. H. MERRILL.

COMBINED NOTE BOOK HOLDER AND LINE INDICATOR.

No. 351,120.

Patented Oct. 19, 1886.

ATTOENEYS.

UNITED STATES PATENT OFFICE.

ALBERT H. MERRILL, OF SANFORD, FLORIDA.

COMBINED NOTE-BOOK HOLDER AND LINE-INDICATOR.

SPECIFICATION forming part of Letters Patent No. 351,120, dated October 19, 1886.

Application filed February 11, 1886. Serial No. 191,657. (No model.)

To all whom it may concern:

Be it known that I, ALBERT HERVE MERRILL, of Sanford, in the county of Orange and State of Florida, have invented a new and useful Improvement in Combined Note-Book Holders and Line-Indicators, of which the following is a specification, reference being had to the annexed drawings, forming a part thereof, in which—

10 Fig. 1 is a front elevation. Fig. 2 is a rear elevation with the cover of the note-book-holding mechanism removed. Fig. 3 is a transverse section taken on line xx in Fig. 2. Fig. 4 is a transverse section taken on line yy in Fig. 1. Fig. 5 is a detail view of the pawl-and-ratchet mechanism by which the line-indicator is moved.

Similar letters of reference indicate corresponding parts in the different figures of the 20 drawings.

The object of my invention is to provide a simple and efficient note-book holder and line-indicator for the use of type-writers and others.

My invention consists in a board supported 25 upon a standard or by attachment to the type-writing machine, and provided with a clamping device for holding the note-book, and in the combination therewith of a line-indicator and pawl-and-ratchet mechanism for moving the 30 line-indicator down the page of the note-book, as hereinafter more fully described.

The board A, forming the body of the book-holder, is provided with a cleat, u , at its lower end for engaging the edge of the book, and to 35 the center of the back of the board is secured a socket, B, for receiving the rounded end of the arm C, which supports the board, the end of the arm C being clamped in the socket by a thumb-screw, b . The arm C is curved, and 40 its outer end is arranged at right angles to the part received in the socket B, and is slotted to receive the edge of the frame of the type-writing machine, and provided with a set-screw, c , for binding it to the frame.

45 By means of the arm C and its adjustment in the socket B the board A may be held at any desired inclination. Instead of employing the arm C, the board A may be supported by a standard in the usual way.

50 In a casing, d , arranged transversely across the back of the board A, near the upper end

thereof, I place two slides, e e' , having arms f f' projecting inwardly toward the center of the board A, and oppositely arranged with respect to each other, the arms f being guided by rollers g , journaled in the casing. The outer ends of the slides e are bent at right angles, extending outward beyond the front face of the board A, and are bent inward over the face of the board A and a short distance from it, to 55 form hooks e'' , for engaging the edges of the note-book cover. Near the center of the casing d is pivoted an equal-armed lever, h , which is connected with the slides e e' by links i i' . The lever h is arranged diagonally in the casing between the ends of the arms f f' , and to the casing are secured springs j j' , which bear upon opposite ends of the lever and draw the slides e e' inward toward the center of the board A. To the lower end of the lever h is pivoted 60 a rod, k , which extends downward along the center of the board A, through a recess formed in the under side of the socket B, through a guide, l , fastened to the back of the board A, near the lower end thereof, and is finally bent 65 forward below the lower edge of the board A, where it is within easy reach of the operator. When the rod k is pushed upward, the lever h is turned, pushing the links outward, causing the slides e e' to separate, so that the cover of 70 the note-book placed on the front of the board A is received between the hooks e'' , formed of the ends of the slides e e' .

Upon one edge of the board A is secured a longitudinally-slotted bar, m , in which is placed 75 a ratchet-bar, n , whose lower end extends downward through an ear, o , and is provided with a head, p . Between the head p and the ear o , and on the shank of the ratchet-bar, is placed a spiral spring, q , which tends to press the 80 ratchet-bar downward. The movement of the ratchet-bar n is limited by slots r , formed therein, and pins s , passing through the slotted bar m and through the slots r of the ratchet-bar n . A rod, t , arranged parallel with the ratchet- 85 bar n , and supported in arms u , projecting from the edge of the board A, forms a guide for the slide v , which is placed thereon and carries the line-indicator w . In the slide v is formed a 90 chamber for receiving the shank b' of the pawl c' , having teeth corresponding to the notches 95 of the ratchet-bar n . The head of the pawl c'

is oblong, and is received in a slot formed in the end of the slide v , and the movement of the pawl c' is limited by a pin, d' , passing through the shank of the pawl c' and through 5 slots in the slide v , the pin d' being provided with rounded heads k' on opposite sides of the slide v . The spring a' presses the pawl c' outward into engagement with the ratchet-bar n . To the back of the slide v is secured a plate, 10 l' , which extends over the rear surface of the board A , and is bent or returned upon itself for receiving the bar m' , which is supported from the back of the board A by short standards n' . The bar m' is arranged parallel with the 15 ratchet-bar n , and forms a guide for the slide v , preventing it from turning on the rod t , and it also holds the pawl c' in place.

The note-book from which the copy is to be taken is placed on the board A under the line- 20 indicator w , the line-indicator being then moved to the first line on the page. After the first line is copied the ratchet-bar is pushed upward against the pressure of the spring q by pressing on the head p . This operation brings the 25 pawl c' into engagement with a new set of notches in the ratchet-bar n , so that when the ratchet-bar is released the spring q will press it downward, carrying with it the slide v and the line-indicator w . The slots r in the ratchet- 30 bar are arranged so that when the ratchet-bar is moved as far as the slots r will permit and then released the line-indicator will be moved downward over the face of the note-book through a distance equal to the space between 35 the lines of the note-book. The slide v is prevented from moving upward when the ratchet-bar is raised by the friction of the slide v on

the rod t and the friction of the plate l' on the bar m' .

When it is desired to move the line-indicator from the bottom of the board A to the top, the pawl c' is disengaged from the ratchet-bar n by moving the heads k' , connected therewith, outward, when the slide v and the line indicator may be readily moved.

Having thus described my invention, what I claim as new, and desire to secure by Letters Patent, is—

1. In a note-book holder, the combination, with the board A , forming the body of the holder, of the case d , slides $e e'$, lever h , links $i i'$, connecting the ends of the lever with the slides $e e'$, springs $j j'$, and the rod k , connected with the lever h , and extending through the lower end of the board A , substantially as herein shown and described.

2. The combination, with board A , of the rod t , the slide v , placed on the rod, the ratchet-bar n , the spring acted pawl c' , the line indicator w , the bar l' , connected to ratchet-bar n , and receiving bar m' , supported upon short standards $n' n'$, secured to the back of the board A , substantially as and for the purpose set forth.

3. The combination, in a note-book holder and line-indicator, of the board A , slides $e e'$, and means for operating the same, the ratchet-bar n , the rod t , slide v , provided with the pawl c' , and the line-indicator w , carried by the slide, substantially as herein shown and described.

ALBERT H. MERRILL.
